DESIGN FOR A BOTTLE CLEANING MACHINE

Herbert Rosengren, Woodcliffe Lake, N. J., assignor to Pneumatic Scale Corporation, Limited, Quincy, Mass., a corporation of Massachusetts

Application March 15, 1939, Serial No. 83,585

Term of patent 14 years

To all whom it may concern:

Be it known that I, Herbert Rosengren, a citizen of the United States, residing in Woodcliffe Lake, in the county of Bergen and State of New Jersey, have invented a new, original, and ornamental Design for a Bottle Cleaning Machine, of which the following is a specification, reference being had to the accompanying drawing, forming part thereof.

Fig. 1 is a front perspective view of a bottle cleaning machine showing my new design; and Fig. 2 is a rear perspective view thereof.

The side of the article illustrated, not shown, is substantially plain.

I claim:

The ornamental design for a bottle cleaning machine, as shown and described.

HERBERT ROSENGREN.
